UNITED STATES PATENT OFFICE.

GAYLE D. STEWART, OF TOLEDO, OHIO, ASSIGNOR TO THE AMERICAN BOTTLE COMPANY, OF TOLEDO, OHIO, A CORPORATION OF OHIO.

DESIGN FOR A BOTTLE.

Application filed December 26, 1924. Serial No. 11,799. Term of patent 14 years.

To all whom it may concern:

Be it known that I, GAYLE D. STEWART, a citizen of the United States, residing at Toledo, in the county of Lucas and State of Ohio, have invented a new, original, and ornamental Design for Bottles, of which the following is a specification.

The figure is an elevation view of a bottle, showing my new design. An elevation view of the opposite side of the bottle is identical with that shown in the figure.

I claim:

The ornamental design for a bottle, substantially as shown.

Signed at Toledo, in the county of Lucas and State of Ohio, this 22 day of December, 1924.

GAYLE D. STEWART.
